UNITED STATES PATENT OFFICE.

WINFORD CARLOS STARKEY, OF FLORENCE, ALABAMA.

COLLAPSIBLE CRATE.

Application filed December 22, 1924. Serial No. 757,438.

To all whom it may concern:

Be it known that I, WINFORD CARLOS STARKEY, a citizen of the United States, residing at Florence, in the county of Lauderdale and State of Alabama, have invented a new and useful Collapsible Crate, of which the following is a specification.

This invention relates to collapsible crates for shipping poultry and the like.

The object of the invention is to provide a crate of this character which is strong and durable and when set up for use is rigid and strong and which may be readily knocked down and occupy a minimum amount of space.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a top plan view of a crate constructed in accordance with this invention set up ready for use;

Fig. 2 is a side elevation thereof;

Fig. 3 is an end elevation;

Fig. 4 is a transverse section taken on the line 4—4 of Fig. 1;

Fig. 5 is a side elevation of the crate shown in folded position; and

Fig. 6 is a transverse section of the folding crate.

In the embodiment illustrated, the crate constituting this invention comprises a bottom 1 preferably composed of wood, to the opposite sides of which are hingedly connected side members 2 and 3. To the ends of said side members are hingedly connected end members 4 and 5. All of these members are composed of substantially rectangular steel frames covered with heavy mesh wire.

The side members 2 and 3 are exactly alike and their combined width corresponds to the width of the bottom 1 so that when these members are folded flat on said bottom member when the crate is collapsed as shown in Fig. 6 they will snugly fit on the bottom and provide a support for a detachable top member 10 which corresponds in size to the bottom member 1 and is also made in the form of a steel frame covered with a

heavy wire netting 11 similar to that used on the side and end members.

The frame of each side member is made substantially rectangular in form and composed of a top rod 6, a bottom rod 7 and end rods 8 with an intermediate rod 9 connecting said top and bottom rods. The top rod 6 projects at its ends beyond the end rods and is provided with bifurcations 12 which straddle the end rods of the adjacent end members as is shown clearly in Fig. 2.

Loops 13 are swiveled to the ends of the bottom rod 7 and extend laterally relatively thereto and are designed to receive cooperating loops 14 formed at the lower ends of the end members 3 and 4 and which extend transversely relatively to said members. The loops 13 are split to permit the engagement therewith of the loops of the end members. The end members 3 and 4 are similarly constructed to the side members except that they have no intermediate cross rod and the loops 14 formed in the ends thereof are slidably engaged with the loops 13 to provide for the proper folding of these members when in collapsed position as will be hereinafter more fully described.

The detachable top member 10 is made in the form of a substantially rectangular frame composed of longitudinally extending laterally spaced steel rods 16, four of which are here shown connected by end rods 17 and over which is arranged a heavy wire netting. The rods 16 are provided at their ends beyond the end rods 15 with bifurcated heads 18 positioned to straddle the top rods 3^a and 4^a of the end members and interlockingly engage therewith when the crate is in set up operative position. A hinged door 19 is formed in the top 10 to afford access to the interior of the crate and which is here shown secured by a latch 20.

The end members 3 and 4 when in upright operative position are connected by rods 21 carried by one member and cooperating rods 22 carried by the other member and which are adjustably connected by turn-buckles 23. These turn buckles 23 have pivot connection with the rods 21 and threaded connection with the rods 22 so that they may be turned for drawing these rods toward each other and thus securely locking the end members in engagement with the top member.

The bottom member 1 is shown provided midway its width with metal lined sockets

1^a designed to receive lugs 25 which project laterally downward from the bottom rod of the end members and which operate as stops to limit the longitudinal movement of the 5 end members in the loops 13 and to hold said end members in proper position for cooperative engagement with the other members of the crate.

A coiled spring 24 is attached at one end 10 to the top rod 4^a of one of the end members and is adapted to be detachably connected with the top rod of the other end member when these members are in folded collapsed position as shown in Fig. 5 of the drawings.

15 In the use of this crate when the parts are in set up operative position as shown in Figs. 1 to 4 and it is desired to collapse the 20 crate for shipping or other purposes, the turn buckles 23 are first unscrewed from the rod 22 which releases the end members and permits them to be swung outwardly a sufficient 25 distance to disengage the bifurcated ends of the rods 16 of the top 10 and permit 30 said top to be lifted off the crate. The side 35 members 2 and 3 are then folded down toward each other flat on the bottom member 1 as shown in Figs. 5 and 6 in which position the loops 13 carried by said members extend 40 upward as shown in Fig. 5. The top member 10 is then laid on top of the folded side 45 members and the end members 3 and 4 are raised in the loops 13 and folded downwardly toward each other over the top member 10 as shown in Figs. 5 and 6. When 50 so folded the coiled spring 24 carried by one end member is engaged with the other end member as shown in Fig. 5 and the parts will be securely locked in collapsed position.

To set up the crate when it is in folded position the operation is reversed. The coiled 40 spring being disengaged from the end member with which it is detachably connected, said end members are swung upwardly to permit the top to be lifted out and then the 45 side members are swung upwardly and the bifurcated heads carried thereby engaged with the end members. When in this position the top is inserted with the bifurcated heads thereof engaged with the cross bars at 50 the upper end of the end members and these end members are secured together by the turn buckle carried rods as above described which lock the parts in operative position holding them rigidly and solidly against all 55 possible collapse.

I claim:—

1. A collapsible crate comprising a bottom having side members hingedly connected

thereto, end members hingedly connected to the ends of said side members, and loosely 60 engaged therewith to permit the end members to be folded down over the side members when the crate is collapsed, said end and side members having means for interlocking engagement when in upright operative position, a top having means for detachable connection with the end and side members, and means for locking said top engaged with 65 said members.

2. In a collapsible crate, a bottom, side 70 members hingedly connected to said bottom, end members having a sliding and pivotal connection with the ends of said side members, said end and side members having means for interlocking engagement when in 75 upright operative position, a top, and means for locking said top engaged with said members.

3. A collapsible crate comprising a bottom having side and end members hingedly connected thereto, said side members having forks for interlocking engagement with the end members when in upright operative position, a removable top having means for interlocking engagement with said end members, and means to detachably connect said end members and hold them engaged with the top member. 80

4. In a collapsible crate, a bottom, side members hingedly connected to said bottom, 90 end members having a sliding and pivotal connection with said side members at the ends thereof, a removable top having fork heads at its ends for interlocking engagement with the end members when in set up 95 position, and adjustable rods connecting said end members to hold them engaged with said top member.

5. In a collapsible crate, a bottom, side members hinged to said bottom, loops extending laterally from the lower corners of 100 said side members, end members having loops engaged with the loops of said side members to adapt them to move toward and away from the side members when in 105 folded position, and a coiled spring for connecting said end members when folded to hold the parts securely together.

In testimony that I claim the foregoing as my own, I have hereto affixed my signature in the presence of two witnesses. 110

WINFORD CARLOS STARKEY.
